UNITED STATES PATENT OFFICE.

GEORGE SCHUBERT, OF WALNUT, TEXAS.

GEAR-SHIFTING MECHANISM FOR CONVEYERS FOR HARVESTERS.

SPECIFICATION forming part of Letters Patent No. 471,197, dated March 22, 1892.

Application filed July 15, 1891. Serial No. 399,558. (No model.)

To all whom it may concern:

Be it known that I, GEORGE SCHUBERT, a citizen of the United States, residing at Walnut, in the county of Bosque and State of Texas, have invented a new and useful Gear-Shifting Mechanism for Conveyers for Harvesters, &c., of which the following is a specification.

This invention relates to an improvement in a gear-shifting mechanism for a reciprocating conveyer for harvesters and binders.

The object of this invention is to secure compactness and efficiency in the gear-shifting mechanism and promote simplicity and cheapness in the construction in such mechanism.

My invention consists in the construction and combination of parts, as will be herein-after described and claimed.

Referring to the drawings, Figure 1 is a plan view of a harvester-platform provided with my improvement. The upper plate is partly broken away, so as to show the mechanism below. Fig. 2 is a front view of the gearing and the inner portion of the platform with the finger-bar removed. Fig. 3 is a stubble end view of Fig. 1. Figs. 4, 5, 6, and 7 are detail views of parts of the mechanism. Fig. 8 is a sectional view on line 1 1, Fig. 1, the strip *a* and the sprocket-wheel beyond the section-line being shown in full lines. Fig. 9 is an enlarged side view of the cam *j*. Fig. 10 is an edge view of the serrated bevel-pinion, and Fig. 11 is a plan view of the rear or serrated side of the said bevel-pinion.

In the drawings, *A* designates the upper plate of the platform, and *A'* the lower plate.

B designates the finger-bar, provided with the usual guards *B*² and a shoe *B'*.

a and *a'* are strips forming walls for the passage of the conveyer *b*, the strip *a*² forming the rear sill of the platform. Said strips *a*, *a'*, and *a*² are of proper width to provide room between the plate *A* and *A'* for the mechanism hereinafter described. The plates *A* and *A'* are secured to the finger-bar and the strips *a*, *a'*, and *a*². A slot *b*' is left in the upper plate *A*.

*b*² are notches formed in the inwardly-projecting edges of the plate *A* near each end of the platform, as shown in Fig. 1, for the operation of the conveyer *b*.

The strips *a* and *a'* are discontinued near the stubble end of the platform to provide room for the shaft *f*. The strip *a* is cut down 55 at *P*² and at *P*³ for the operation of the levers *P* and *n*. The finger-bar *B* is provided with a vertical flange *B*⁴ near its stubble end to meet the plate *A*. Said plate *A* is slightly elevated near the stubble end of the platform 60 to provide room for the gearing beneath it.

*b*⁴ is the ordinary grain-board, secured to the plates *A* and *A'* and the finger-bar *B* in any well-known manner.

f designates a shaft located near the stubble 65 end of the platform and journaled with its rear end in a pivoted bearing *J* and with its front end in a movable bearing *h* and provided with a sprocket-wheel *i* near the center of the slot *b*' and adjacent the pivoted bearing *J*, a collar *J*², adjacent the rear side of the pivoted bearing *J*, a bevel-pinion *f*' on its front end adjacent the front side of the movable bearing *h*, and a collar *J*³, adjacent the rear side of the movable bearing *h*, thus preventing any rearward or forward movement 70 of the movable bearing *h*. The pivotal bearing *J* rests on a block *A*², secured to the plate *A'* and held in position by the bolt *J*', extending through the plate *A'* and the block *A*² and screwed partly into the pivoted bearing *J*.

*f*⁴ designates a shaft provided with a bearing *f*⁵, secured to the finger-bar *B* in line with the pivoted bearing *J*. Bevel-pinions *f*² and 85 *f*³ are secured to the shaft *f*⁴, adjacent each side of the bearing *f*⁵ and in position for the bevel-pinion *f*' to be engaged or disengaged therewith.

h designates a movable bearing, prevented 90 from moving, when not so desired, by the spring *h*', which is secured to the block *h*² and of proper length to extend over the movable bearing *h*. Said block *h*² is secured to the plate *A'* and of proper length to provide 95 a support for the movable bearing *h*. Said movable bearing *h* is constructed about as shown in Fig. 7, which shows a plan and a front view of same. The bearing is provided with a perforation *h*⁵ to receive the shaft *f* and with the downward projections *h*³ *h*³, adapted to rest properly on the block *h*², and studs *h*⁴ *h*⁴ project forward from near the ends of the bearing, as shown, of proper length to receive

the cams j and j' . Said cams j and j' are pivoted with their lower ends to the studs h^4 h^4 and their other ends project upward and are connected together by the bar j^4 .

- 5 j^2 j^3 are anti-friction rollers rotating on studs j^7 j^7 , secured in the upper ends of the cams j and j' . Said studs j^7 also pivotally connect the bar j^4 to the cams j and j' .

In Fig. 4 is shown an enlarged edge view of 10 one of the cams provided with the anti-friction roller j^3 , the cam j being lightly serrated j^6 and the rear side of the bevel-pinion f^2 also being serrated f^9 , as shown in Figs. 10 and 11, to prevent the cam j from disengaging with said bevel-pinion when not so desired. The bar j^4 is provided with a stud j^5 near its center.

n designates a lever pivotally secured to the stud j^5 on the bar j^4 and pivoted on a pin n^2 , 20 which extends with its upper end through the plate A and with the lower end through the finger-bar B, adjacent the vertical flange B^4 and on line with the pivoted bearing J. The front end n' of said lever n is provided with 25 a draw-rod n^3 , which is extended to the operator's seat. (Not shown in the drawings.) The other end of said lever projects rearward into the passage-way of the conveyer b, and is slightly curved grainward, as shown in 30 Fig. 1, and connected to the lever P by the rod P'. Said lever P is preferably pivoted at its front end to the plate A and projects toward the rear with its rear end in the passage-way of the conveyer.

35 In Fig. 2 the front end of the lever n is shown broken away.

t t' are lugs secured in the block h^2 a proper distance apart and provided with set-screws t t' to regulate the limit of movement of the 40 movable bearing h , thus regulating the mesh of the bevel-pinion f with the bevel-pinions f^2 and f^3 .

P^4 and P^5 are brackets secured to the strip a a proper distance apart to limit the movement of the lever n , thus preventing any unnecessary pressure of the anti-friction rollers j^2 and j^3 against the bevel-pinions f^2 and f^3 .

i' designates a chain extending over the sprocket-wheel i and a sprocket-wheel i^2 near 50 the grain end of the platform. Said sprocket-wheel i^2 is secured near the center of the slot b' on a shaft i^4 , which has its bearings in the strips a and a' .

The operation is as follows, viz: The shaft 55 f^4 receives its movement from gearing of the harvester, (not shown,) and is rotated in the direction shown by the arrow in Fig. 3. When the operator desires to start the conveyer, he draws the draw-rod n^3 , thus shifting the rear 60 end of lever n and the upper end of the cams j j' grainward, thus engaging the cam j' and anti-friction roller against the bevel-pinion f^3 , which forces the lower end of the cam and the movable bearing stubbleward, thus engaging the bevel-pinion f' with the bevel-pinion f^3 , thereby starting the conveyer. As 65 the conveyer nears the stubble end of its

movement it moves against the lever n , shifting it along in the same direction, or stubbleward, thereby moving the upper ends of the 70 cams stubbleward, thus disengaging the anti-friction-roller j^3 from the bevel-pinion f^3 and engaging the cam j with the bevel-pinion f^2 . Said cam j being slightly serrated or notched, j^6 will remain in engagement with the bevel-pinion f^2 until it has passed said bevel-pinion f^2 and been disengaged by the anti-friction roll j^2 , thus shifting the movable bearing grainward, which disengages the bevel-pinion f' from the bevel-pinion f^3 and engages it 80 with the bevel-pinion f^2 , thereby reversing the movement of the conveyer, and as the conveyer nears the grain end of its movement it moves toward the lever P and moves it grainward, thus moving the rear end of the 85 lever n and the upper end of the cams j and j' in the same directions, disengaging the anti-friction roller j^2 and engaging the cam j' with the bevel-pinion f^3 , which forces the movable bearing stubbleward, and thus disengages the 90 bevel-pinion f' from the bevel-pinion f^2 , thus discontinuing the movement of the conveyer. The cam j' , being smooth, will not shift the bearing h the entire distance stubbleward without pressure against its upper end toward 95 the bevel-pinion f^3 , received from the draw-rod n^3 , as heretofore described.

Having thus described my invention, and not wishing to be understood as confining my 100 claims of invention to the precise form or proportion of parts herein shown and described so long as the principles of construction and mode of operation are essentially the same as that herein set forth, what I claim, and desire to secure by Letters Patent, is—

1. In a gear-shifting mechanism for harvesters, a bevel-pinion secured to a shaft mounted in a bearing h , supported to slide on a beam or block h^2 , said bearing being provided with studs h^4 h^4 , having cams j and j' pivoted thereto, said cams j and j' pivotally connected by a bar j^4 and provided with anti-friction rollers j^2 and j^3 , said cams and anti-friction rollers in position to engage or disengage with the bevel-pinions f^2 and f^3 for 110 the purpose described, a lever n , pivoted to the bar j^4 and pivoted to the harvester-platform and provided on its forward projecting end n' with a draw-rod n^3 , as shown, and for 115 the purpose described.

2. In a gear-shifting mechanism for harvesters, a bevel-pinion secured to a shaft mounted in a bearing h , supported to slide on a beam or block h^2 , said bearing being provided with studs h^4 h^4 , having cams j and j' pivoted thereto, said cams j and j' pivotally connected by a bar j^4 and provided with anti-friction rollers j^2 and j^3 , the cam j serrated for 120 the purpose described, said cams and anti-friction rollers arranged in position to engage or disengage with the bevel-pinions f^2 and f^3 , a lever n , pivoted to the bar j^4 and to the platform, as shown, extending with one end toward the rear, as shown, and a conveyer 125

moving in the platform, as shown, and for the purpose described.

3. In a gear-shifting mechanism for harvesters, a shaft f , journaled with its rear end in a pivoted bearing J and provided with a sprocket-wheel i , carrying a chain i' to operate the conveyer, a movable bearing h for supporting the shaft f , said bearing being supported to slide on a block or bracket secured to the platform and provided with studs h^4 h^4 , having cams j and j' pivoted to said studs h^4 h^4 in position to engage with the bevel-pinions f^2 and f^3 , anti-friction rollers j^2 and j^3 on the upper or free ends of said cams, a bar j^4 , connecting said cams and provided with a stud j^5 , a lever n , pivoted to the stud j^5 and to the frame of the machine, and a spring h' , secured with one end to the platform and with its other end resting on the movable bearing h , as shown, and for the purpose described.
4. In a gear-shifting mechanism for harvesters, a bevel-pinion secured to a shaft mounted in a bearing h , supported to slide on a block or bracket h^2 , said bearing being provided with studs h^4 h^4 , having cams pivoted to said studs, anti-friction rollers on said

cams, the cams and anti-friction rollers in position to engage with the rear side of the bevel-pinions f^2 and f^3 , a bar j^4 , connecting the free end of said cam and provided with a stud j^5 , a lever n , pivoted to the stud j^5 and to the frame of the machine, and lugs t t' , secured in the block or bracket h^2 and provided with set-screws t' t' , as shown, and for the purpose described.

5. In a gear-shifting mechanism for harvesters, a bevel-pinion secured to a shaft mounted in a bearing h , supported to slide on a block or bracket h^2 , said bearing being provided with studs h^4 h^4 , having cams pivoted to said studs, anti-friction rollers on said cams, the cams and anti-friction rollers in position to engage or disengage with the bevel-pinions f^2 and f^3 , a bar j^4 , connecting the free end of said cams and provided with a stud j^5 , a lever n , pivoted to the stud j^5 and to the frame of the machine, and brackets P^4 and P^5 , secured to the platform or to the strip a , as shown, and for the purpose described.

GEORGE SCHUBERT.
